UNITED STATES PATENT OFFICE.

WILLIAM F. HANSE, OF NEW YORK, N. Y., ASSIGNOR TO THE J. T. PERKINS COMPANY, OF SAME PLACE.

OIL-PRESS MAT.

SPECIFICATION forming part of Letters Patent No. 611,316, dated September 27, 1898.

Application filed January 19, 1898. Serial No. 667,141. (No model.)

To all whom it may concern:

Be it known that I, WILLIAM F. HANSE, a resident of the city of New York, (Brooklyn,) in the county of Kings and State of New York, have invented certain new and useful Improvements in Oil-Press Mats, of which the following is a specification.

My invention relates to the production of an efficient oil-press mat.

10 In pressing oil from seeds it is customary to employ a series of mats upon which the seeds are placed and the whole compressed in a press, which squeezes the oil out from the seeds, the oil which remains in the mat being 15 extracted afterward. It has been found, however, that these mats rapidly wear away at their middle portions, owing to the fact that the greatest strain is brought to bear at that portion of the mat. Various schemes have 20 been devised to obviate the bad effects of these strains, which, as will be well understood, rapidly destroyed the mat. None of these devices have been successful. For instance, it has been proposed to employ metallic wires laid alongside the warp-threads 25 of the mat, but it has been found that these wires not only cut the warp-threads, but, having little elasticity, break and produce rapid deterioration of the mat. All these defects 30 are overcome by my invention.

My invention will be understood by referring to the accompanying drawings, in which—

Figure 1 is a face or plan view of an oil-press mat embodying my invention. Fig. 2 is a section on line 2 2 thereof.

In this mat *a* are the weft-threads, which are bound in with the warp-threads *b* in any usual manner, the fabric shown in the drawings being substantially a twill fabric. The warp-threads at the middle portion of the fabric are crowded together more than at the edges of the fabric and are in greater num-

bers at the middle than at the edges, as shown. I prefer to gradually decrease the number of 45 warp-threads per inch from the center to the edges of the fabric in any desired proportion. The fabric is preferably made of camel's hair, as I have found that camel's hair, among other qualities, "strips" easier than other materials 50 heretofore employed.

What I claim, and desire to secure by Letters Patent, is—

1. As a new and useful article of manufacture, the herein-described oil-press mat having warp-threads and weft-threads, the warp-threads at the middle portion of the fabric being in greater numbers per inch than the warp-threads at the edges of the fabric, whereby the fabric is strengthened at the point 60 where the greatest strain is applied.

2. As a new and useful article of manufacture, the herein-described oil-press mat, comprising warp-threads and weft-threads, the warp-threads at the middle of the mat being 65 in greater numbers per inch than at the edges of the mat, and gradually decreasing in numbers per inch from the middle of the mat toward the edges, substantially as described and for the purposes set forth.

3. An oil-press mat comprising a twill fabric composed of camel's-hair threads, the warp-threads of the fabric being in greater number per inch at the middle portion of the fabric than at the edges.

4. An oil-press mat comprising a twill fabric composed of camel's-hair threads, the warp-threads of the fabric being most numerous at the middle of the fabric and decreasing in numbers per inch gradually on both sides of 80 the middle of the mat, substantially as described.

WILLIAM F. HANSE.
